USPC **D28/58**

CLAIM

(58) **Field of Classification Search**

The ornamental design for a pedicure device, as shown and described.

USPC D7/669, 697, 213; D24/133, 146, 171, D24/211, 212, 213, 214, 231; D28/57, D28/58, 99

DESCRIPTION

CPC A45D 29/00; A45D 29/007; A45D 29/17; A45D 29/18; A45D 29/04; A45D 29/05; A45D 29/11; A45D 29/14; A45D 29/20; A45D 2200/1054; A61B 17/54; A61B 2017/00424

FIG. 1 is a front perspective view of a pedicure device of the present invention showing our new design;

See application file for complete search history.

FIG. 2 is another perspective view thereof;

FIG. 3 is a front elevational view thereof;

FIG. 4 is a rear elevational view thereof;

FIG. 5 is a side elevational view thereof;

FIG. 6 is an opposing side elevational view thereof;

FIG. 7 is a top view thereof; and,

FIG. 8 is a bottom view thereof.

The broken lines shown herein depict portions of the device that form no part of the claimed design.
